[57] CLAIM

The ornamental design for a mirror, as shown and described.

DESCRIPTION

FIG. 1 is a front view of an embodiment of the design.

FIG. 2 is a front, left side perspective view of the embodiment of the design, and the front, right side perspective view is a mirror image; and,

FIG. 3 is a right side view of the embodiment of the design and the left side view is the mirror image.

The broken lines are for environmental purposes only and form no part of the claimed design.

The rear and bottom views of the embodiment of the design are of a plain, non-ornamental back and bottom, respectively.
